HIGHWAY SIGNAL

Jarrett Hiram Burden, Mount Vernon, Ill., assignor of one-half to Claude C. Hall, Mount Vernon, Ill.

Application April 23, 1935, Serial No. 17,871

4 Claims. (Cl. 40—125)

This invention relates to a signal device for use on highways to indicate to approaching traffic that an obstruction, such as a parked car, men at work, etc. is located a short distance ahead.

Many accidents have been caused by the enforced parking of vehicles on highways, particularly at night and it is designed to provide a signal especially useful to motorists who desire to warn approaching traffic that a car is parked ahead.

A further object is to provide a signal device which can be folded compactly and thus easily transported in a vehicle, it being possible to quickly unfold the device and set it up for use.

A still further object is to provide the signal device with indicating characters such as letters or the like formed preferably of reflectors so that they will be clearly legible when illuminated by the headlights of an approaching vehicle.

A still further object is to provide a signal device one surface of which can be utilized for holding advertising matter so that the complete device, which can be inexpensively manufactured can thus be distributed either free, or at a very low cost, because of its advertising value.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a front elevation of the signal device opened for use.

Figure 2 is an elevation showing the same collapsed or folded for convenient storage.

Figure 3 is an enlarged section on line 3—3, Figure 2.

Figure 4 is an enlarged section on line 4—4, Figure 1.

Referring to the figures by characters of reference, 1 designates a pintle in the form of a rod one end of which is formed with a sleeve-like extension 2 having a longitudinal slot 3 from the sides of which extend ears 4. Supported in this slotted portion of the sleeve with one end pivotally connected to the ears as indicated at 5, is a stem 6 having an intermediate offset portion 7 providing a step or foot piece while the free end of this stem is preferably pointed as shown at 8 although it is to be understood that said end can

be otherwise shaped to facilitate erection of the signal device at the point of use. The stem 6 is so shaped that when in one extreme position it will rest within the sleeve 2 and aline with the pintle 1 and when in its other extreme position it will be folded so as to extend along the pintle as shown by dotted lines in Figure 1.

Sleeve 2, which is joined to the pintle, can be made integral with one edge portion of a wing 9 formed preferably of a suitably shaped metal plate 10 and this wing can be provided with additional shorter sleeves 10 spaced apart and also joined to the pintle 1. Another wing 11 preferably of the same shape and material as the wing 9 is provided with sleeves 12 rotatably mounted on the 15 pintle 1 between the sleeves 10 and 2 so that the two wings are thus hingedly connected and can fold one upon the other. A spring 13 is preferably coiled about a portion of the pintle and has its terminals 14 extended in opposite directions 20 and bearing against the respective wings so as to hold them normally spread apart and substantially in alinement, their relative movement under the action of the spring being stopped by the wings coming together at those edges from which 25 the sleeves are extended.

When the wings are folded together the spring will be placed under increased tension and they can be held folded by means of a pivoted clip 15 connected to one of the plates and adapted to be 30 swung into position so as to straddle both plates when brought together or folded as in Figures 2 and 3.

Arranged on those faces of the wings or plates 9 and 11 which are adapted to be folded together, 35 is any suitable arrangement of characters which can be in the form of letters, figures or symbols. In the drawing there have been shown letters comprising the words "Car parked" and these letters are formed of buttons 16 containing reflectors and of any suitable color so that when the headlight of an approaching vehicle is directed against the open signal device the letters formed by the buttons will become illuminated and can be readily deciphered by the approaching motorist. 45

For the purpose of lightening the device slots 17 can be formed in the wings and these slots are also advantageous because they permit light rays to pass in either direction through the signal device to serve as a warning.

Normally the signal device is folded as shown in Figures 2 and 3. Thus it can be conveniently carried in a vehicle because of the small space which it will occupy.

Should a situation develop wherein it becomes 55

desirable to set up the signal device to warn of approaching danger, it merely becomes necessary to shift the clip 15 so as to release the plates or wings and permit them to swing open under the action of spring 13. Stem 6 is then swung downwardly into alignment with the pintle 1 and as the slotted portion of the sleeve 2 is slightly contracted along slot 3, with the walls of the slot flared as shown particularly in Figure 4, the stem will snap into the slotted sleeve and thus be retained in extended position. After the parts have thus been adjusted the stem is forced into the surface of the road or into any suitable supporting member resting thereon. To facilitate the erection of the signal the offset portion 7 has been provided so that a foot of the user can be employed for exerting downward pressure upon the stem.

After the signal device has served its purpose and its use is no longer necessary it can be quickly collapsed or folded as heretofore explained and stored for future use.

As has already been stated those surfaces of the wings opposite the ones on which the buttons 16 are displayed can be made flat so that suitable display matter for advertising purposes can be applied thereto.

The slots 17 not only have the advantage heretofore stated but also reduce wind resistance so that the danger of the signal being blown down is reduced greatly.

What is claimed is:

1. A signal device of the class described including hingedly connected wings foldable one upon the other, an indicator carried by the wings, a spring placed under tension by the folding of the wings, a ground engaging supporting stem joined thereto and foldable into position therebetween, means for detachably holding the wings in folded position, said spring constituting means for automatically moving the wings apart when relieved from the restraining action of the holding means

and means for stopping the relative movement of the wings when brought into alignment.

2. A signal device of the class described including hingedly connected wings, a stem hingedly connected thereto and foldable therebetween, means for holding the stem against accidental displacement when in extreme unfolded position, means for holding the wings folded together, means for automatically moving the wings apart when released from the restraining action of said holding means, and a reflecting indicator carried by the wings and adapted to be exposed by the unfolding of the wings.

3. A signal device including hingedly connected wings, an indicating means thereon adapted to be exposed when the wings are unfolded, means for holding the wings folded together, means for automatically unfolding the wings to expose the indicating means when the wings are released from the restraining action of the holding means, a supporting stem hingedly connected to the wings and foldable therebetween to one extreme position and movable therefrom to its other extreme or wing supporting position, and a clip gripping means for holding the stem in the last named position against accidental displacement.

4. A signal device including hingedly connected wings, an indicating means thereon adapted to be exposed when the wings are unfolded, means for holding the wings folded together, means for automatically unfolding the wings to expose the indicating means when the wings are released from the restraining action of the holding means, a supporting stem hingedly connected to the wings and foldable therebetween to one extreme position and movable therefrom to its other extreme or wing supporting position, a clip gripping means for holding the stem in the last named position against accidental displacement and a step upon the stem.

JARRETT HIRAM BURDEN.
